UNITED STATES PATENT OFFICE

HERBERT DANIEL AUE, OF BLOOMFIELD, NEW JERSEY

TRAVELER FOR KITE STRINGS

Application filed May 23, 1932. Serial No. 613,079.

The purpose of this invention is to provide a saddle by which a parachute may be sent along a kite string to a point near the kite and launched with an attached weight or figure. The object is to provide a device for this purpose of inexpensive construction.

In the accompanying sheet of drawing which forms a part of this description,

Figure 1 is a perspective of the traveler, parachute and attached figure as arranged when traveling up the kite string.

Fig. 2 is a perspective of the opened and descending parachute.

Fig. 3 is a plan of a sheet from which the saddle and its sail are formed.

Fig. 4 is a perspective of a modified form of traveler.

A stiff sheet of paper is folded to form a saddle with side sections 10 and sail sections 11. The sheet is sharply folded longitudinally part of the way as indicated by the full line 12 on the plan of the sheet, and is reversely folded partially or bent or curved where indicated by the dotted line 13. Transverse and inclined partial folds, bends or creases radiate from the junction point of the reversed longitudinal folds and are indicated by the dotted lines 14. All of the dotted lines indicate bends or folds in the same direction.

Folded in this manner the sheet is formed into a saddle and sails as shown, suitable to rest on a kite string and to be propelled by the wind. The sharp fold provides a ridge over which a folded parachute sail 15 lies. A forked figure 16, which may be suitably carved from a clothes pin, sets over the parachute sail on the saddle ridge. The forks are spaced so that the figure will not clamp the folded parachute tightly. The parachute shrouds 17 are loosely wound around the figure.

In the modified form shown in Fig. 4, ridges 18 are provided in the sides of the saddle by slots cut therein and the folded parachute sails are laid over them. This provides for sending up two parachutes at the same time by the traveler.

The traveler arranged as shown in Figs. 1 or 4 is placed on the kite string 19. When the wind has carried it up to the kite or as

far as desired, a side jerk of the string suffices to throw off the figure which falls and drags off the parachute sail.

I claim:

1. A kite-string traveler consisting of a saddle formed with a ridge and sails, a parachute with a sail adapted to be folded and laid over the saddle ridge, and a forked figure connected to the parachute shrouds and adapted to loosely engage the parachute sail. 55

2. A kite-string traveler consisting of a saddle formed from a sheet with longitudinal folds reversed with respect to each other and transverse folds with a ridge along one of the longitudinal folds and with sails, a parachute with a sail adapted to be folded and laid over the saddle ridge, and a forked figure connected to the parachute shrouds and adapted to loosely engage the parachute sail. 60

3. A kite-string traveler consisting of a saddle formed from a sheet with longitudinal folds reversed with respect to each other and with transverse folds and sails and with slots in the sides forming ridges, parachutes with sails adapted to be folded and laid over the saddle ridges, and forked figures connected to the parachute shrouds and adapted to loosely engage the parachute sails. 75
